UNITED STATES PATENT OFFICE.

JACINTO VENDRELL, OF BARCELONA, SPAIN.

LOOM.

Application filed May 29, 1924, Serial No. 716,728, and in Spain March 7, 1924.

This invention relates to automatic stopping mechanism for looms having fixed reeds, which mechanism comes into operation when the shuttle does not reach the end 5 of its course. The mechanism of the invention presents over those known up to the present the advantage of producing the stopping with complete absence of shock by which damage produced in looms as the consequence of violent arrest is avoided, and by 10 which a notable increase in efficiency results since in addition to permitting the operation at a greater speed, it is not necessary for the loom to be stopped, for the repairs thus rendered necessary.

It is known that the diminution in the length of the connecting rod which transmits the movement of the crank shaft to the beater increases the time available for the 20 passage of the shuttle, and the invention has for its object to utilize this increase in time for giving a greater extent of movement than the normal to the stop commonly called the frog, which serves to cause the arrest when 25 the arm commonly called the stop rod dagger or finger operable by the tongues of the shuttle boxes comes to be engaged.

The movement of the stop which in ordinary looms is about a centimeter, may owing 30 to the shortening of the connecting rod be more than three centimetres, and this increase permits of obtaining a progressive braking of the fly wheel of the crank shaft before (the movement of the stop having 35 terminated) the total interruption of the operation is produced. For obtaining this progressive braking, the rod connecting the stop to the brake operating member is constituted of two or more parts articulated in such 40 manner that while the said stop drawn by the arm bearing upon it effects traction upon the rod, the parts are displaced one with reference to the other or to the others, over-coming the action of one or a number of 45 springs which tend to maintain them in the position which corresponds to the minimum length of the rod, simultaneously actuating the said brake operating member with a force progressively greater according as the 50 distension of the said springs increases. In this way it becomes possible for the loom to operate at a greatly reduced speed.

The invention is diagrammatically illustrated by way of example in the accompanying drawings, in which Figure 1 is a side elevation and Figures 2 and 3 respec-

tively cross sectional end elevation and plan on an enlarged scale showing the manner of connection of the parts 6, 7 and 9.

As illustrated in the accompanying drawings, the stop or frog 1, in the notch of which engages to the extent required the arm or the stop rod dagger or finger which serves to cause the arrest, is mounted separate from the breast plate 3 of the loom 60 and is connected to the shoe 4 of the brake of the fly wheel 5 of the crank shaft by a rod formed of two parts 6 and 7, of which the part 7 is constructed as a fork, in which is 65 exactly enclosed the head of the part 6 in which is provided a hole or slot 8. This part 6 has a downward extension carrying a pin 17 upon which are pivoted two small parallel disposed levers 9, pivoted also upon a pin 10 which traverses the slot or hole 8 75 in the part 6, the levers being connected at the upper part by another pin to which is connected at one extremity the spring 11, which by reason of its disposition can be distended to an extent greater than corresponds to the relative displacement of the 80 parts 6 and 7. For restoring the parts to the position of normal operation of the loom, the stop 1 is submitted constantly by means of a rod 13 to the action of a strong spring 85 14 fixed to the frame 15 by the studs 16, 16.

The operation of the mechanism is as follows: The stop 1 drawn by the arm or stop rod dagger or finger engaging its notch 90 2 draws the rod 6 and 7 which causes the application of the shoe 4 upon the fly wheel 5 with a slight pressure at first, but increasing progressively according as the part 7 drawn by the stop 1 and the part 6 retained by the shoe 4 causes the tension of the spring 95 11 to increase.

The stop 1 carries a finger or projection which from the first moment of engagement of the arm upon it operates to throw the loom out of gear in causing the belt to pass 100 from the fixed pulley of the crank shaft to the loose pulley, after which during the movement of the said stop it produces the progressive braking of the movement through the inertia possessed by the fly 105 wheel, the total arrest being effected finally, when the speed of the crank shaft having then diminished, the stop 1 arrives at the end of its movement and the brake operating rod is no longer extended owing to the 110 fact that the pin 10 has passed along the slot 8 a distance proportional to the move-

ment of the stop and has reached the end of the slot.

It will be understood that the operation of the mechanism produces the stopping without shock, whereby the possibility of damage is avoided notwithstanding that the loom is operated at a high speed which permits of the employment of a short rod for transmitting the movement of the crank

10 shaft to the beater.

I claim:

1. In looms having fixed reeds, a crank shaft, and a frog adapted to be engaged by a stop rod dagger or finger to actuate the 15 stopping mechanism, the combination of stopping mechanism comprising a brake shoe, means such as a fly wheel mounted upon the crank shaft of the loom to co-operate with the said brake shoe, a draw 20 rod connecting said frog and said brake shoe, the said draw rod consisting of two parts movable longitudinally with respect to one another, means of connection between the parts of the said draw rod providing lost 25 movement between the said parts, and means comprising a spring by which the relative movement of the parts of the said draw rod

causes the gradual application of pressure by the brake shoe until the lost movement between the parts of the draw rod is taken up, substantially as hereinbefore described. 30

2. In looms having fixed reeds, a crank shaft, and a frog adapted to be engaged by a stop rod dagger or finger to actuate the 35 stopping mechanism, the combination of stopping mechanism comprising a brake shoe, means such as a fly wheel mounted upon the crank shaft of the loom to co-operate with the said brake shoe, a draw rod connecting said frog and said brake shoe, said draw rod consisting of two parts movable longitudinally with respect to one another, means of connection between the parts of the said draw rod providing lost movement 40 between the said parts, a spring, and means comprising a lever connected to the said spring and by which relative movement of the parts of the said draw rod causes the extension of the spring and the gradual application of pressure by the said brake 45 shoe until the lost movement between the parts of the said draw rod is taken up, substantially as hereinbefore described. 50

JACINTO VENDRELL.
